UNITED STATES PATENT OFFICE

158,950

GAME BOARD

Jasper W. Fleming, Kansas City, Mo.

Application November 10, 1948, Serial No. 149,567

Term of patent 14 years

(Cl. D34—5)

To all whom it may concern:

Be it known that I, Jasper W. Fleming, a citizen of the United States, residing at Kansas City, in the county of Jackson and State of Missouri, have invented a new, original, and ornamental Design for a Game Board, of which the following is a specification, reference being had to the accompanying drawing, forming part thereof, in which:

Fig. 1 is a plan view of a game board showing my new design, and

Fig. 2 is an edge view of the game board shown in Fig. 1.

Color differences are indicated by differences in the degree of stippling.

I claim:

The ornamental design for a game board, substantially as shown and described.

JASPER W. FLEMING.
